UNITED STATES PATENT OFFICE.

PERCY NUGENT AVERY, OF GRAPPENHALL, NEAR WARRINGTON,
ENGLAND.

VICE.

No. 806,620.

Specification of Letters Patent.

Patented Dec. 5, 1905.

Application filed March 21, 1905. Serial No. 251,274.

To all whom it may concern:

Be it known that I, PERCY NUGENT AVERY, director of companies, a subject of the King of Great Britain, residing in Grappenhall, 5 near Warrington, in the county of Chester, England, have invented certain new and useful Improvements in Vises, (for which application has been made in Great Britain, No. 23,087, dated October 26, 1904,) of which the 10 following is a specification.

This invention has for its object an arrangement of vise which can be clamped on the bar of a gate or other like support, such as can be found along any highway. This is very desirable in motoring, as there is no part of a motor, as a rule, to which a vise can be temporarily attached in this way, and ordinary vises cannot without very considerable trouble and defacement of the article on which 15 they are fixed be attached to a gate-bar or the like. It is, moreover, a most useful tool for electricians, plumbers, and others.

In the accompanying drawings, Figure 1 is an elevation of my device open; Fig. 2, the 20 same in section closed.

The device comprises two jaws A and B, pivoted together at the base at C.

a b are the gripping edges of the jaws. Between these two gripping edges an object can 25 be clamped securely, leaving both hands free for work. Through one of these jaws B a hole is bored from the back to the front below the gripping portion of the jaw. This is screw-threaded. A long screwed pin D, having a 30 part d close to the head D' left unscrewed, is provided with a clamp member E, loose on the pin D, but fitting with a good fit, and capable of hanging on the pin D at right angles thereto, but prevented by the accurate fit 35 from taking any but a position at right angles to it and parallel with the outside of the jaw B. This pin D, which is free to turn in the clamp member E, is screwed through the hole in the primary jaw B. The other end of the 40 pin is passed loosely through a hole a' in the auxiliary jaw A and provided on the opposite side with a fly-nut F. The jaw B on the outside and the opposing face of the clamp member E are serrated at J. It will be noticed 45 that the same pin which closes the jaws A and B holds the device to a fixed object, such as the rail G of a gate.

The mode of action is as follows: The

screwed pin D being screwed out of the jaw B until the clamp member E stands at some distance from it, the article is placed over, say, 55 the rail G of a gate or other object with the clamp member E on one side of the rail and the jaw B on the other. It is now screwed up by turning the head D' of the pin D by 60 means of a spanner applied to its head or by means of a bar passed through a hole H therein until jaw B is tight up against the rail G on one side and the clamp member E on the other. It will then be quite firm and stand 65 any amount of strain. The article to be held can now be placed between gripping edges of the jaws and the fly-nut F screwed up until the jaws hold the article tightly. The jaws are opened by a spring I, which separates the 70 jaw A from B when the fly-nut F is unscrewed. The pin D also acts as an abutment against G to prevent the vise slipping down.

I declare that what I claim is—

1. A vise comprising two jaws (with gripping edges) hinged together at one end, a threaded pin screwed through a threaded hole in one jaw and passing freely through a plain hole in the other, a clamping member mounted at one end of this pin and disposed 80 in a plane parallel to one jaw in such a manner, that by screwing up the pin the said member and jaw can be made to hold tightly on some fixed object, and a nut at the other end of the pin for closing up the other jaw to 85 hold an article between the gripping edges.

2. A vise comprising two jaws or members A B with gripping edges, a pin threaded for its entire length (except at a part close to the head) screwed through a threaded hole in 90 one jaw A below the gripping edges and passing through a plain hole in the other B, a clamping-plate mounted at one end of the pin next the head on the unthreaded part so as to lie parallel to its adjacent jaw B, and 95 the opposing faces toothed or serrated, and a nut at the other end of the pin, whereby by screwing up the pin by its head, the vise can be clamped to some fixed object with the clamp at one side and the jaw B at the 100 other, or by screwing up the nut at the other end of that pin, the other jaw A is—without unclamping the device—closed up to hold an article between its gripping edges.

3. In a device of the character described, 105 the combination of a threaded member, a

primary jaw threaded upon said member, a laterally-adjustable, auxiliary jaw positioned upon said member and movably connected to said primary jaw, means for securing said auxiliary jaw in an adjusted position, and a clamp member carried by said threaded member.

4. In a mechanism of the class described, the combination of a primary jaw, a member threaded into said jaw, a clamp member carried by said threaded member, a freely-movable, auxiliary jaw carried by said primary jaw and positioned upon said threaded member, and means for independently adjusting said clamp member and said freely-movable, auxiliary jaw.

5. In a device of the character described, the combination of a revolute member, primary and auxiliary pivotally-mounted jaws carried by said revolute member, a clamp member carried by said revolute member, said clamp member adapted to be adjusted relative to said primary jaw by imparting movement to said revolute member, and longitudinally-movable means carried by said revolute member and adapted to adjust said auxiliary jaw relative to said primary jaw.

6. In a device of the character described, the combination with a revolute member, of a pair of jaws mounted upon said revolute member, revolute means carried by said revolute member and adapted to adjust one of said jaws relative to the other jaw, and a clamp member carried by said revolute member, said clamp member adapted to be

adjusted relative to said jaws by means of rotating said revolute member.

7. In a device of the character described, the combination with a pair of pivotally-connected jaws, a clamp member, a revolute member extending through said clamp member and said jaws and connecting the same, and independent means for adjusting said jaws and clamp member.

8. In a device of the character described, the combination of a pair of pivotally-connected jaws and a clamp member, a spring interposed between said jaws, revolute means extending through said clamp member and said jaws, said revolute means adapted to adjust said clamp member relative to said jaws, and longitudinally-adjustable means carried by said revolute means and capable of adjusting one of said jaws relative to the other jaw.

9. In a device of the character described, the combination of a clamp member, a pair of jaws, rotary means supporting said clamp member and connecting said jaws, said rotary means adapted to adjust said clamp member, and an independent rotatable member coacting with said rotary means for adjusting one of said jaws.

In witness whereof I have hereunto signed my name, this 3d day of March, 1905, in the presence of two subscribing witnesses.

PERCY NUGENT AVERY.
